UNITED STATES PATENT OFFICE.

CLAUDE L. POST, OF CHICAGO, ILLINOIS.

SHEET-FEEDING CONTROL MEANS.

Application filed March 24, 1923. Serial No. 627,455.

This application is a continuation in part of my application, Serial Number 591,107, for envelope feeding mechanism, and relates to improvements in sheet-feeding control means, and particularly to such a mechanism for use in conjunction with a printing press, or the like, wherein sheets, envelopes, etc., are fed at high speed through the press.

One of the objects of my invention is to provide means for automatically preventing contact between the platen and the type whenever there is no sheet or envelope passing through the printing rolls.

Another object of my invention is to provide means for rendering the drive inoperative whenever the means for preventing contact between the type and the platen is actuated.

Many other objects and advantages of the construction herein shown and described will be obvious to those skilled in the art from the disclosures herein given.

To this end my invention consists in the novel construction, arrangement and combination of parts herein shown and described, and more particularly pointed out in the claims.

In the drawings, wherein like reference characters indicate like or corresponding parts,

Fig. 1 is a side elevation showing my device as applied to a printing press;

Fig. 2 is a vertical sectional view through the press;

Fig. 3 is a fragmentary elevation showing the means for controlling the drive shaft of the printing press;

Fig. 4 is an enlarged fragmentary plan view of the platen and type rolls, showing the means for preventing contact therebetween and for releasing the drive when there is no envelope passing between the rolls;

Fig. 5 is a sectional view taken substantially on line 5—5 of Fig. 4;

Fig. 6 is a sectional view taken substantially on line 6—6 of Fig. 4; and

Fig. 7 is a fragmentary sectional view taken substantially on line 7—7 of Fig. 5.

In the preferred form of construction, as shown in the drawings, I have illustrated the device as used in connection with a press for feeding envelopes from a magazine, conveying them between a pair of printing rolls and thence discharging them in a pile at the rear end of the press. It is to be understood, however, that my device is not lim-

ited to use for envelopes, but it may be used for feeding any other similar objects or materials, such as sheets or the like therethrough.

1 represents a supporting frame for the printing mechanism, the same being adapted to be suitably supported by or mounted upon a cooperating structure or table so that it will be of the right height for most efficient operation. In this device, the envelopes are retained in a magazine or the like, and are automatically fed successively, one at a time through printing rolls and are then automatically discharged and stacked up for removal.

The printing rolls comprise a pair of rolls 2 and 3 respectively, the former being the type roll and the latter the platen roll, and through which the envelopes or sheets must pass to be imprinted. These rolls are driven positively in unison through any form of gearing, or the like, and in any desired manner, 21 indicating the shaft upon which the type roll is mounted, both of said rolls rotating at the same rate of speed. It is to be noted, however, that the platen roll 3 has the ends of its shaft 4 mounted in eccentrically bored bushings 5, as shown more clearly in Figs. 4 and 5 of the drawings, for a purpose to be more clearly hereinafter described.

The magazine 6 for holding the envelopes is preferably removably arranged on the frame at a distance from the printing rolls and the envelopes are automatically fed successively through the printing rolls in any desired manner.

In order that the type roll and the platen roll shall not come together whenever there is no envelope being fed therethrough, the shaft 4 is mounted in eccentric bushings 5, as has been heretofore described. Connected to one of the bushings is a lever 7, so that when the lever is rocked or pivoted, the bushing will be oscillated to lower the rotational axis of the shaft 4 and thus separate the rolls 2 and 3.

A gear segment 8 is operatively connected to the lever 7 and is adapted to mesh with a pinion 9 of a shaft 10 mounted at both the sides of the frame, the other end of the shaft 10 (not shown) having a pinion thereon similar to the pinion 9 and intermeshing with a gear segment similar to segment 8, the latter being rigidly connected to an eccentric bushing at the other end of the

shaft 4. In this manner both the eccentric journals at the ends of the roll will be actuated simultaneously.

A cam member 11 is drivingly connected 5 to the shaft 21 of the roll 2, but is slidable longitudinally thereof, said cam being of such a contour that it will actuate the lever 7 only when rotating in the same plane therewith. An abutment or stationary cam 10 12 is carried on the frame 1 to engage the rotary cam 11 and to retrieve said cam to a position out of registry with the lever 7, but guiding said cam into registry therewith whenever said cam is slid longitudinally 15 of the shaft of the type roll (to the right). A coiled spring 13 is interposed between the rotary cam 11 and the adjacent end of the type roll, the same constantly urging said rotary cam (to the right) into 20 operative engagement with the lever 7.

In order to permit the spring 13 to operate only at such time as when there is no envelope being fed between the printing rolls, a pin 14 having an enlarged head 15 25 at its end, is rigidly carried by the cam 11 and projects inwardly of the inner side thereof, said enlarged head having a pair of substantially parallel bevelled surfaces at its sides for a purpose to be more clearly 30 hereinafter described.

A rocker shaft 16 is mounted within the roll 2, the same having at one end a fork member 17, whose prongs are bevelled at 35 their inner opposed surfaces to correspond with the bevelled sides of the enlarged head 15 of the pin 14, said shaft 16 carrying a lever arm 18 at its other end, as shown in Fig. 6: The arm 18 is mounted so as to be movable inwardly below the envelope-contacting 40 surface of the roll 2, and to be moved to project outwardly therebeyond whenever there is no envelope being fed between the rolls. A spring 19 may be positioned at some suitable point, as for instance 45 at the fork 17 in order to normally urge the fork outwardly, if so desired, although generally the centrifugal force will of itself be sufficient to urge the fork outwardly.

The operation of the means for separating 50 the printing rolls is as follows:

The parts being in the position shown in full lines, let us assume that there is no envelope in readiness for insertion between the printing rolls. The spring 13 constantly 55 presses the rotary cam 11 toward the stationary cam 12, said cam 11 being free to move toward the right because the enlarged head 15 of the pin 14 is in position to permit such sliding movement through the fork (see Fig. 4). The continued rotation of the 60 cam 11 will cause it to slide off the cam 12 and move into the plane of the rocker arm 7, engaging said arm or lever and actuating it to cause the separation of the rolls, the cam 11 again engaging the cam 12, the lat-

ter pushing the cam 11 back to the left out of registry with the arm 7 (see Fig. 4), and the parts all resuming their full-line position shown in the drawings, after each separation of the rolls. A spring 20 may be 70 positioned to engage the rocker arm 7 to return it to its normal position after its actuation thereof. As soon as an envelope is in position for insertion between the rolls, the arm 18 will strike said envelope and 75 move inwardly (see Fig. 6), thereby rocking the part 17 to interlock it with the pin 14, as shown in dotted-line position in Fig. 7, so as to prevent the spring 13 from sliding the cam 11 to the right. Thus in each 80 rotation of the printing rolls the parts assume the full-line positions shown in the figures of the drawings, so that the cam 11 will be moved to the right in case there is no envelope between the rolls, or that the 85 arm 18 will be pressed inwardly to lock the cam 11 against movement in case there is an envelope in position for feeding.

In addition to the means for separating the printing rolls whenever there is no 90 envelope being fed therethrough, I have provided means for cutting off the drive for the mechanism at such times. A drive shaft is provided which has a driving connection with the shaft 21 of the printing roll 2 as 95 shown in Figure 4. On this shaft there is a drive wheel 22, in the present instance this wheel being frictionally driven by means of a friction wheel 23 normally in contact therewith. The wheel 22 is keyed to the 100 shaft 21 and it is obvious that the rotation of the driving-wheel 23, when in frictional contact with the wheel 22, will cause rotation of the drive-shaft 21.

A spring 24 may be interposed between 105 the wheel 22 and the end of the shaft to releasably urge the driving means in operative engagement. A bracket 26 is carried by the frame, either integral therewith or as a separate part, and having a bore through 110 which the shaft 21 extends. The rock-shaft 10 has a rocker-arm, or crank, 27 at its end, the same formed with an elongated opening or slot 28 therethrough. A lever 29 is revolvably mounted on the drive-shaft 21, intermediate the drive-wheel 22 and the bracket 26 and forming an end-bearing for said drive-wheel. A radial projection 30 is formed at the upper end of the lever 29 and a corresponding recess 31 is formed in the 120 opposed surface of the stationary bracket 26, as shown, so that when the projection 30 is seated in the recess 31, the friction disk 22 will be in operative engagement with the friction driving-wheel 23, the spring 24 125 tending to keep the parts in such engagement.

It is obvious that if the lever 29 is rocked about the shaft 21, the projection 30 will become unseated from the recess 31, causing 130

the lever to move laterally of the shaft axis (to the right) to move the friction-disk 22, against spring pressure of the spring 24, out of engagement with the driving-wheel 23, and thus shut off the drive of the shaft 21. The lower end of the lever 29 is formed with a hook 32, which is adapted to be removably inserted through the slot 28 of the member 27.

10 Whenever the eccentric bushings 5 are rotated to separate the printing rolls, the shaft 10 is rocked in the direction indicated by the arrow in Fig. 1, whereby the lever 29 is correspondingly rocked about the 15 shaft 21 and is moved laterally to release the driving-wheels 22 and 23 from engagement. As soon as the shaft 10 resumes its normal position, the lever 29 will again seat in the groove 31, the spring 24 tending to 20 hold it in place.

Having thus described my invention, it is obvious that various immaterial modifications may be made in the same without departing from the spirit of my invention; 25 hence I do not wish to be understood as limiting myself to the exact form, construction, arrangement and combination of parts herein shown and described or uses mentioned.

20 What I claim as new and desire to secure by Letters Patent is:

1. In combination with a pair of rolls, means for separating said rolls, a cam rotatably actuated by one of said rolls and 35 engageable to actuate said separating means whenever there is no material being fed through the rolls, means carried by said roll and controlled by the material being fed through the rolls for operating said rotatable cam, and a stationary cam engageable with said rotary cam for retrieving it from engagement with said first-mentioned separating means.

2. In combination with a pair of rolls, 45 means for separating said rolls, a cam rotatably driven by one of said rolls and adapted to be moved into the path of and to engage with and actuate said separating means whenever there is no material being fed through the rolls, a stationary cam engageable with said rotatable cam to retrieve it out of the path of said separating means, and means carried by said roll for normally maintaining said rotatable cam in inoperative 50 position, but permitting it to be moved to operative position whenever there is no material being fed between the rolls.

3. In combination with a pair of rolls, a 60 rotatable cam slidably longitudinally of one of said rolls and driven thereby, means for separating said rolls and including a rocker arm adapted to be actuated by said cam to effect the actuation thereof, a stationary cam for retrieving said rotatable cam from its rocker operating position, a spring for

urging said rotatable cam into operative position, a member carried by and projecting from said rotatable cam, and a member carried by said roll to overlie said last-mentioned projecting member and interlock therewith to normally prevent the sliding movement of said rotatable cam, but permitting said movement when there is no material passing between the rolls.

4. In a device of the kind described and in combination, a pair of rolls, one of said rolls having a cam rotatably driven thereby and slidable axially thereof, means for separating said rolls including a rocker arm adapted to be engaged by said cam, a stationary cam engaging said rotary cam to permit it to be moved into or out of operative engagement with said rocker arm, a spring for urging said rotatable cam into its operative position, a pin projecting from said rotatable cam and having an enlarged head, and a fork member carried by said roll to overlie said enlarged head and interlock with said pin to normally prevent the sliding of said rotary cam when material is being fed between the rolls, but automatically operative to permit said sliding whenever there is no material passing therethrough.

5. In a device of the kind described and in combination, a pair of rolls, a lever pivotally carried thereby and engageable with the sheets passing between said rolls, a fork operatively connected to said lever, a rotary cam driven by and slidable longitudinally of one of said rolls and provided with a pin thereon having an enlarged head interengageable with said fork to normally prevent longitudinal movement of the cam, a spring pressing said cam longitudinally, roll-separating means including a rocker lever operatively engageable with said cam at its outward limit of longitudinal movement, and means engageable with said cam to guide it out of its operative position.

6. In combination with a pair of rolls adapted to have material fed therethrough, a drive-shaft operatively connected with one of said rolls, a drive-wheel on said drive-shaft, a second wheel drivingly engageable with said drive-wheel, means for resiliently holding said wheels in operative engagement, and means automatically operable when there is no material being fed therethrough to release said wheels from such engagement.

7. In a device of the kind described and in combination, a pair of rolls, a drive-shaft operatively connected with one of said rolls, a drive-wheel carried on said shaft, a second drive-wheel drivingly engageable with said first-mentioned drive-wheel, means resiliently holding said wheels in engagement, means for separating said rolls when there is no material being fed therethrough, and

means operable by said last-mentioned means to move said drive means apart when said last-mentioned means is actuated.

8. In combination with a pair of rolls adapted to have material fed therethrough, a drive-wheel drivingly connected to said rolls, a second drive-wheel operably engageable with said drive-wheel, means for separating said rolls whenever there is no material being fed therethrough, and a lever automatically actuated by said last-mentioned means to shift said drive wheels out of engagement.

9. In combination with a pair of rolls, a drive-shaft operatively connected with one of said rolls and having a drive-wheel slidably mounted thereon, a second drive-wheel operatively engageable with said first-mentioned drive-wheel, means for normally keeping said drive-wheels in engagement, means for separating said wheels when there is no material being fed therethrough, and means operable by said last-mentioned means for shifting said first-mentioned

drive wheel laterally of said shaft to release it from driving engagement with the other wheel.

10. In combination with a pair of rolls, a shaft operatively connected with one of said rolls, a friction-wheel carried by said shaft, a second wheel operably engageable with said first-mentioned wheel to transmit drive therebetween, a rock-shaft, a lever having one end engageable with said rock-shaft and actuated thereby, the other end adapted to be positioned intermediate said first-mentioned drive-wheel and a stationary part, and an engaging lug and recess between said last-mentioned end of the lever and said stationary part, whereby when said lever is rocked by said rock-shaft it will be moved out of engagement at said lug and recess and be shifted laterally to move said first-mentioned friction-wheel out of engagement with the second wheel.

In testimony whereof, I have hereunto signed my name.

CLAUDE L. POST.
